AIR CONDITIONING APPARATUS

Henry L. Galson, Philadelphia, Pa., assignor to
 Baldwin-Southwark Corporation, a corporation
 of Delaware

Application December 24, 1932, Serial No. 648,772

72 Claims. (Cl. 62—129)

This invention relates generally to air conditioning apparatus and more particularly to an improved room cooler and ventilator for offices and homes.

- 5 In my present invention I have provided a self-contained portable room cooling unit employing a refrigerating system, the unit being so constructed and arranged that it may be conveniently placed in a room ready for immediate operation and will efficiently operate with utmost quiet and effectiveness so that occupants of the room will not be annoyed either from noises or drafts. I have also provided in one specific embodiment of the invention as shown 10 herein an air cooled condenser contained within the unit, the unit and condenser being so arranged that the condenser heat may be adequately taken care of without affecting the room temperature. In a more specific aspect 15 of the invention I have arranged the unit in an improved manner so that it will be highly compact and require minimum floor space whereby it may be placed adjacent a suitable opening in a wall of the room such as a window and at the same time insure that a large volume of outside 20 air may be efficiently conducted into and out of the unit with full effectiveness in cooling the condenser. This improved arrangement necessitates blowers of only moderate size and the 25 blowers and passages are so functionally related so as to obtain maximum volumetric capacity for the outside condenser cooling air even though the unit is compact and extends outwardly from the room wall for only a minimum distance. In 30 addition to obtaining proper flow of the outside condenser cooling air in a compact unit, I am also able to insure proper and efficient flow of room air through the unit by providing an improved structural and functional relation between 35 the various elements embodied in my unit. Irrespective of the type of condenser cooling system employed there are other improved features associated with my particular condenser cooling system so as to effectively adapt the unit for use 40 in a home or office without unsightly appearance or mechanical complications.

In addition I have provided a unit that is not only compact so as to require minimum space but is also adapted to have an attractive exterior 45 design and from a mechanical standpoint to have a relatively large refrigeration capacity to effect the desired degree of humidity control and air cooling. Inasmuch as the elimination or control of humidity is an essential factor in air conditioning, the room cooler is arranged in an improved

manner to adequately and efficiently take care of the eliminated humidity. In my invention the unit is so constructed and the parts so arranged that mechanically it may be economically manufactured in quantity production while maintaining high quality of workmanship and operation together with the utmost reliability when in the hands of the users.

It is one object of my invention to accomplish the foregoing and other results in a room cooler which is relatively inexpensive for a piece of apparatus of this character and yet will have an improved combination of elements so arranged and related that the unit has a high degree of compactness and simplicity of construction, design and arrangement of parts, and has improved means for effecting exterior atmospheric communication with the refrigerating equipment including the refrigerant condenser, although there are various features of the room cooler as disclosed herein that are applicable either to a water cooled condenser or to a room cooler employing refrigerating systems other than the compressor-condenser-expander circuit which is a specific form shown. It is also an object of my invention to have the elements of the unit highly adapted for manufacture and assembly in quantity production while at the same time permitting them to be readily accessible and easily dismantled or removed in case of the necessity of repair or replacement.

Another object is to provide improved means for collecting condensate resulting from the elimination of humidity which condenses on the evaporator and of ejecting or discharging this condensate to the atmosphere outside of the room, this being accomplished specifically by collecting the condensate in a pan or trough beneath the evaporator and conducting the condensate to an ejector pan beneath the condenser, whereby the condenser cooling air in blowing upwardly through ejector openings causes the water to be entrained in the stream of air and to be discharged to the exterior atmosphere although in being so discharged the moisture will be blown 45 against the condenser to assist in cooling the same by re-evaporation.

A further object is to provide an improved room cooler adapted to effect positive ventilation 50 by introducing into the room a portion of preferably filtered, cooled and dehumidified outside air, preferably under pressure and to either directly or indirectly exhaust a proportional amount of devitalized room air to the outside, and

to accomplish such ventilating or other air circulation without draft within the room.

Other objects and advantages will be more apparent to those skilled in the art from the following description of the accompanying drawings in which:

Fig. 1 is a perspective of the room cooler unit shown principally from the rear side thereof, the unit being partially broken away to show details of the arrangement of elements;

Fig. 2 is a vertical transverse section taken substantially on the line 2—2 of Figs. 1 and 3, parts being broken away to show details of construction;

Fig. 3 is a rear elevational view of the unit with parts broken away to show the air filters, fans and path of flow for the condenser cooling air;

Fig. 4 is a rear elevational view similar to Fig. 3 but showing only the fan for the room air and the path of flow thereof;

Fig. 5 is a plan view of the unit;

Fig. 6 is a rear view perspective of the cabinet alone;

Fig. 6a is a section of a dummy control button shown relative to the actual switch buttons, the section being taken on line 6—6 of Fig. 6;

Figs. 7 and 8 are sections of cabinet details respectively taken on lines 7—7 and 8—8 of Figs. 1 and 6, except Fig. 6 omits the back panel;

Fig. 9 is a perspective of the main frame of the unit with the rear side of the frame in the foreground;

Fig. 10 is a perspective of the joints for the duct-supporting members;

Fig. 11 is a perspective of the base joint for the intermediate standards;

Fig. 12 is a perspective of the base joint for the end standards, looking up at the bottom thereof;

Figs. 13, 13a and 13b are perspectives, respectively, of the evaporator and its associated frame, and the intermediate and lower air ducts, these three elements when assembled forming a unit or sub-assembly conduit for room air;

Fig. 14 is a vertical section through one side of the sub-assembly unit of Figs. 13, 13a and 13b;

Figs. 15, 15a and 15b are perspectives, respectively, of the condenser and its frame, the ejector pan for accumulating and discharging water condensed from the cooled room air, and a duct communicating directly with the cooling fan, the condenser, pan and duct normally being assembled to form an assembly unit, hereinafter also called a condenser assembly;

Fig. 16 is a vertical section through one side of the condenser assembly of Figs. 15, 15a and 15b;

Fig. 17 is a fragmentary perspective of the supporting frame for the fan motor;

Fig. 18 is a vertical transverse section taken on the line 18—18 of Fig. 12;

Fig. 19 is a perspective of a modified form of support for the fan motor;

Fig. 20 is an enlarged fragmentary vertical section, somewhat similar to the right end of Fig. 3, showing the ventilator and filter support more in detail;

Fig. 21 is a partial end view of the cooler unit showing the air filter in elevation;

Fig. 22 is a horizontal section on line 22—22 of Fig. 21 with parts omitted;

Fig. 23 is an enlarged fragmentary vertical section showing the rods for removably holding the air filter in position;

Fig. 24 is a wiring diagram for effecting an improved coordinated compressor and fan control;

Figs. 25—27 are diagrammatic views of different arrangements for the condenser cooling air;

Fig. 28 is a horizontal section on line 28—28 of Fig. 3 showing the relation of the evaporator, condenser and end plates with the contacting faces thereof secured together by rivets, sheet metal screws or welding.

For purposes of illustrating one specific form which the invention may take, among possible others, I will describe in detail the component parts of the unit although for a comprehensive view of the unit reference should be had to Fig. 1 which is a perspective taken primarily from the rear side thereof.

Main frame.—The main frame of the unit, Fig. 9, comprises preferably two horizontal substantially parallel structural channel members 1 and 2 with the channel flanges facing outwardly.

Structural angle irons 3 and 4, connecting the ends of the channel members, have a corner of their horizontal leg (Fig. 12) cut out as at 5 thus permitting the vertical leg to have an overhanging portion 5' fit against the full depth of the end of the channels while the cut out corner 5 allows the horizontal leg to have butt engagement with the channel web, flush with the lower channel flange. These various joints may be suitably welded together, preferably by a welded seam along any or all of the lines of juncture of the structural members. All four frame corners are of the same construction. Three uprights or standards 6, 7 and 8, provided at three corners of the base frame, are in the form of angle irons which, as shown in Fig. 12, extend down over the corner portion of the flanges of the channels 1 and 2 and also over the portion 6 of the end angle irons 3 and 4, all of these members being secured preferably by welding along any or all of their lines of juncture. It will be understood that the details shown in Fig. 12 also apply to standards 6 and 8. Intermediate standards 9 and 10 are likewise formed of angle iron but in this case the lower ends thereof merely rest on the top flanges of channels 1 and 2 and are provided with an angle clip 11 shown more clearly in Fig. 11, all of these members being preferably welded together along any or all of their lines of juncture to form a rigid construction.

The standards 8, 9 and 10 define the space or compartment for the motor-compressor unit to be described later, the fourth corner of this space not being provided with a standard thus facilitating assembly or removal of the motor-compressor in the cooler unit.

To support an evaporator and a condenser, and ducts therefor, there is provided an upper horizontal frame work. This includes transverse end angle irons 12 and 13. As shown more clearly in Fig. 10 angle irons 12 and 13 have their vertical legs as at 14 disposed on the inside with their ends fitting in the corners of standards 6, 7, 9 and 10 and secured thereto as by welding along any or all of the lines of juncture. Longitudinal angle irons 15 and 16 have their vertical legs disposed on the inside while the ends of these vertical legs are cut out as at 17 to provide a butt joint with the vertical legs of angle irons 12 and 13. The overhanging portions 18 of the longitudinal angle irons 15 and 16 rest upon the transverse angle irons and these are all secured together preferably by a welded seam at any or all of the lines of juncture. It will of course be

75

understood that the enlarged view of Fig. 10 is representative of the joints at the other standards 6, 9 and 10. An intermediate longitudinal support in the form of a relatively wide channel iron 20 has its ends preferably in butt engagement with the vertical legs of the end angle irons 12 and 13 and are secured thereto preferably by welding along the lines of juncture. If desired the various frame members can be secured together by bolts or other suitable means, it being understood however that the particular arrangement of parts as shown herein is best adapted for welding.

The members 15 and 20 define the space in which the evaporator and ducts therefor are disposed while the members 20 and 16 define the space in which the condenser and air ducts therefor are disposed.

Evaporator and air ducts therefor.—The evaporator as shown in Fig. 13 and generally indicated at 24 comprises a series of horizontal tubes 25 whose ends are secured in rectangular headers 26 and 27. Heat radiating fins 28 of the outline preferably similar to headers 26, 27 are secured to or suitably mounted on pipes 25 to increase the heat transfer surface therefor. Side plates 29 and 30, made preferably of sheet metal, have their top and end edges bent outwardly to form flanges 31 and 32 and are secured to the sides of headers 26 and 27 to form what is herein referred to as the evaporator. The lower edges of side plates 29 and 30 are not bent outwardly thus permitting insertion of the side plates within slots of an intermediate air duct to be now described.

As shown in Fig. 13a, the intermediate air duct generally indicated at 34 comprises preferably sheet metal end walls 35 with their lower edges bent outwardly to form flanges 36. Sheet metal side plates 37, provided with flanges 38, are welded, soldered or otherwise suitably secured to end walls 35. Moisture deflecting baffles 39 are formed, as shown more clearly in Fig. 14, by reversely bending the top edge portion of side plates 37, as at 40, and then slanting the baffle portions 39 inwardly but leaving a space between their free edges to permit upward flow of air. While the lower ends of these baffles are spaced apart, yet they overlap a lower V-shaped combined baffle and drip trough 41 which is secured by welding, soldering, riveting or otherwise to the sheet metal end walls 35. This intermediate duct member 34 is provided with a series of slots 42 to removably receive the lower unflanged edges of side plates 29 and 30 of the evaporator these slots being disposed inwardly, from sides 37, as close as possible to permit the outer side of plates 30 to be flush with inner sides of plates 37. The intermediate duct member is permanently secured in a lower duct member generally indicated at 45 in Fig. 13b.

The lower duct member 45, Fig. 13b, is made of a sheet metal front plate or wall 46 and a rear inclined wall 47 joined by end walls 48. The rear inclined wall 47 is turned into a short vertical wall 49. The top edges of walls 46, 48 and 49 are bent outwardly to provide a horizontal shoulder 50 and are then bent upwardly to provide vertical legs 51 prior to assembly with the intermediate duct 34. The corners of the vertical legs are cut out as indicated at 52 to permit them to be bent over the horizontal flanges 36 and 38 of the intermediate duct when the latter is placed upon the horizontal shoulders 50, this assembled relation being shown in

Fig. 14. The bottom of lower duct 45 is entirely closed by a bottom plate 52'. All of the end, side and bottom plates are secured together by welding, soldering or other suitable means. An air inlet opening 53, adapted for communication with a fan to be described later, is located at the right end of the duct and is provided with a flange 54 extending around the opening. A pipe 55 extends through a suitable opening in one of the sides 37 to allow condensate, which drips from the evaporator, to be transferred to an accumulator and ejector pan to be presently described.

As shown in Fig. 14, the intermediate and lower ducts 34 and 35 form a permanent unitary structure adapted to support evaporator 24 all of which, however, forms a unit that is herein termed an evaporator assembly which projects downwardly between and is supported upon longitudinal members 15, 20, 12 and 13 of Fig. 9, 20 the shoulders 50, Figs. 13b and 14, resting upon the top surfaces of these members.

Condenser, air ducts and combined accumulator-ejector pan.—The condenser, Fig. 15, generally indicated at 60 is constructed in a manner 25 similar to evaporator 24 and is approximately of the same dimensions and heat transfer capacity therefor. The condenser tubes 61 are connected into headers 62 and 63 while heat radiating fins 64 of the same general outline as the 30 headers are secured to the condenser tubes. A front sheet metal side plate 65 has its vertical and top edges bent outwardly to form flanges 66 although the lower edge is unflanged while a rear sheet metal side plate 67 has only its ends 35 bent outwardly to provide flanges 68. The sides 65 and 57 are permanently secured to the condenser headers to form the condenser unit.

A combined accumulator and ejector pan generally indicated at 69 comprises preferably a bottom 40 70 whose edge portions are bent upwardly to form sides 71 and are then bent backwardly upon itself as at 72 and then outwardly to form flanges 73. The ends 74 may be part of the sheet metal of bottom 70 or may be formed separately 45 and soldered or otherwise secured with a water tight fit to the sides 71 and bottom 70. The entire bottom 70 has a series of staggered openings 75 formed as by pressing portions of the bottom upwardly to provide four sides 76 around each 50 opening. The juncture of these sides and the bottom being slightly curved to assist in providing an ejector action to entrain condensate accumulated in this pan by an upwardly flowing draft of air. End slots 77 are formed to receive the lower unflanged edges of side plates 65 55 and 57 of the condenser.

Pipe 55 which leads from drip pan 41 is removably inserted through the side of ejector pan 69 to conduct thereto the condensate from the 60 evaporator.

A lower duct 78 comprises vertical sides 79 and ends 80 formed of separate pieces of sheet metal secured together and bent outwardly as at 81 to provide a horizontal shoulder or flange and 65 then bent upwardly as at 82. This vertical flange 82 is later bent over the horizontal flange 73 of the ejector pan 69 of Fig. 15a. The corners of flanges 82 are cut out as at 83 to facilitate such bending over operation. Duct 78 is closed 70 over the largest portion of its bottom as by a sheet metal plate 84 which it will be noted is slightly inclined upwardly from a horizontal portion in which an air inlet 85 is provided with a suitable downwardly extending flange 86. 75

When the elements 69 and 78 are secured together, Fig. 16, as by bending flanges or lips 82 over flanges 73, in the manner previously mentioned, and the lower edges of condenser sides 66 and 67 are set within the slots 77 of Fig. 15a, these three elements then form a unit having the horizontal flange 80' which rests upon frame members 16, 20, 12 and 13, Fig. 9.

The condenser and evaporator assemblies are positioned beside each other in substantially parallel vertical relation and are at least partially suspended from the upper frame in spaced relation to the bottom of the main frame thus providing what might be termed, a blower compartment or space 88, Figs. 1 and 3.

Fans and motor therefor.—To effect the necessary air circulation through the condenser and evaporator assemblies, there is disposed in the blower compartment, as shown in Figs. 1 and 3, electric power means for driving rotatable air circulating means, specifically shown herein as an electric motor 90 whose shaft extends longitudinally of the unit in opposite directions, Fig. 3, to carry at one end a centrifugal rotor 91 of a room air or evaporator blower generally indicated at 92 while the other end of the motor shaft carries a rotor 93 of a condenser cooling blower generally indicated at 94, the motor in the specific form of the invention shown being common to the two blowers which thus have the same speed and hence under certain conditions may be considered as a single blower with a dividing partition. The room air fan 92 is located beneath the upwardly inclined bottom 84 of condenser air duct 78 thus enabling, Fig. 2, the tangential fan outlet 96 of the fan scroll case to have inclined preferably direct communication with the flanged opening 53 of the evaporator duct 45. The condenser cooling fan 94 is disposed immediately below the vertical inlet 85 of the condenser duct 78 thus permitting vertical preferably direct communication with the tangential outlet 97. The two fan outlets are preferably slightly spaced from the edges of the inlets of the respective ducts and are connected thereto as by a suitable strip of rubber or fabric 98, Fig. 1, extending around the joint between the fan outlets and duct inlets. This strip not only provides the necessary air-tight joint but the presence of the space prevents transmission of vibration from the fan scroll to the metallic ducts by obviating any metal to metal contact.

As shown in Fig. 3 and others, the motor and fans are longitudinally disposed within a central zone of the unit frame, specifically with their common shaft and axis substantially on the longitudinal center plane of the unit frame, although the fan outlets extend in different tangential or angular directions with respect to said axis, so that the condenser and evaporator assemblies may be preferably directly connected to the fans without disturbing in any way the balanced relation of said assemblies on substantially each side of the longitudinal center line or vertical plane of the unit. This arrangement provides a well-balanced unit having the highly desirable features of compactness and accessibility.

As shown more clearly in Fig. 17 the motor 90 and blower rotors carried thereby are supported upon a sub-frame having a pair of transverse angle irons 99 and 100 which have bent up ends 101 welded or secured by any suitable means to longitudinal angle irons 102 and 103. These longitudinal angle irons, one of which is shown

more clearly in Fig. 18 as illustrative of the remaining structure, are normally fixed to bolts 104 whose heads are imbedded or vulcanized in a solid, relatively resilient, preferably cylindrical rubber pad 105 while other bolts 106, having heads also imbedded in said pad, project downwardly through the upper flange of channels 1 and 2. The upper bolt 104 with its two nuts permits vertical adjustment of the sub-frame with the blower motor and rotors relative to the fan casings. It will be seen from Fig. 17 that there are four of the rubber supports for the motor thus insuring a non-metallic support which will reduce to a minimum the transmission of vibration to the room cooler unit. It will also be noted that the sub-frame extends considerably to the left beyond motor 90, this being for the purpose of insuring a proper support for the elongated condenser cooling blower which has approximately twice the capacity of the room air blower 92 as shown in Fig. 1, the casings of fans 92 and 94 having suitably curved spring supports 108 and 109 disposed on each side of the respective fan casings secured to the top side of the base channels 1 and 2, said spring supports being welded or otherwise suitably secured to the fan casings and base channels.

In the modified form of motor support shown in Fig. 19 the transverse motor brackets 99' and 100' are connected by cross members 102' and 103', this sub-frame in turn being supported upon longitudinal pieces of rubber 110 secured by bolts to the base channels 1 and 2. Notches 111 formed in the rubber permit bolts 112 to secure the sub-frame to the rubber strip without having metallic contact with the main frame, although if desired pads such as 105, Fig. 18, may be used.

Compressor.—To obtain utmost compactness in the unit and also to effect a desired degree of weight distribution and minimum vibration I provide as shown in Fig. 1 a self-contained vertical axis motor-compressor unit of the piston and cylinder type generally indicated at 113. For purposes of the invention herein disclosed it will suffice to state that the compressor has a vertical axis motor disposed within a suitable cylindrical housing 114 while a compressor casing generally indicated at 115 has horizontal opposed cylinders, the head of one cylinder being shown at 116. The compressor crankshaft and the motor armature shaft are a single piece thus providing a direct drive for the compressor. This motor-compressor unit is supported by a series of four legs 117 formed preferably integral with and extending outwardly from a lower casing 118 of the unit. Two of the legs 117 are supported upon a suitable transverse angle iron 116' which have cut-out corners to permit the horizontal leg of the angle iron to rest on, and preferably be welded to, the top of each of the two base channels 1 and 2 while the other two legs 117' (not shown in Fig. 1, but shown in Figs. 3 and others), are mounted on a transverse angle iron similar to 116. The connections between each of the legs and transverse angle irons are preferably through rubber pads and bolts 105' identical to 105 in Fig. 18.

To secure proper cooling of the motor with as simplified arrangement as possible, I employ in my improved combination the condenser cooling fan 92 to cool the motor. To accomplish this I have provided a cooling coil 119 which specifically is connected to the lubrication system of the motor-compressor unit. As the motor-com-

pressor is of the sealed type, a coil 118 constitutes the primary source of heat radiation for the motor, this coil being disposed over the top of the motor-compressor unit and provided with fins to increase the heat radiating surface. The outlet from the motor casing to the coil is at 120 while the return is at 121 in the top center of motor casing 114.

Although the lubricating cooling system shown 10 employs a cooling coil 118 as the specific embodiment of the apparatus used for effecting motor and compressor heat radiation, any other suitable radiator may be employed, and the same located in any part of either the condenser or 15 room air streams so that the motor-compressor cooling may be effected.

The compressor-condenser-expander circuit for the apparatus may be of any suitable type used 20 in a compression system and hence the piping connections therefor are not shown herein.

Internal top cover, end walls and back plate defining internal ducts and compartments.—Referring to Fig. 1 a sheet metal internal top cover plate 128 extends over the entire top of the main 25 frame and mechanism contained therein. The rear and end edges of this plate are bent upwardly to form a flange 129 while a room air opening 130, provided in the cover, substantially conforms to the space in which the evaporator 30 fins 28 are disposed. The edges of plate 128 around all four sides of the opening 130 are bent upwardly to provide suitable flanges 131. It is thus seen that top plate 128 is in the nature of a shallow pan, particularly if the front edge of the 35 plate should be bent up to provide a flange similar to flanges 129. Suitable insulating material 132 of either loose or molded form may be thus placed entirely over the surface of plate 128 within the confines of the outer edge flanges 129 and the 40 air passage flanges 131. If the insulation is of molded material, it may be suitably fastened to the plate. In Fig. 1, plate 128 and insulation 132 have been appreciably broken away in order to 45 see other details of construction although from the description herein and particularly as shown in Fig. 2 the continuity of the pan-shaped top piece and insulating material can be more easily seen. The plate is preferably supported on the top edges of the various elements of the unit such 50 as the corner standards of the main frame and the flanges 31 and 66 of the evaporator and condenser, the plate being secured thereto as by soldering or sheet metal screws. As a further modification plate 128 and insulation 132 may also 55 be secured by any suitable means to the top of cabinet 153 (to be described later) forming a unitary construction with the cabinet and resting on the top of standards of the main frame when the cabinet is in place. In any event it is seen 60 that a relatively simple and compact insulating top piece is provided together with a suitable room air opening.

To form a partition of the compartments in which the condenser and evaporator are disposed 65 there is provided as shown in Figs. 1 and 3, an end partition plate 134 which preferably is disposed inside of and rests against the transverse leg of angle iron standards 9 and 10, the upper edge of this partition abutting against the under- 70 side of top plate 128 while the lower edge of the partition 134 rests upon the transverse angle iron 12, Fig. 9. This sheet metal partition 134 is held in close contact with angle irons 9 and 10 as by sheet metal screws or bolts so as to permit independent insertion or removal of the evaporator 75

and condenser units without hindrance from the plate 134. The other end of the evaporator and condenser compartments is similarly provided, Fig. 3, with a sheet metal end wall 135 corresponding in every way as to its structure and manner of being held in position except of course its relation is in respect to end standards 8 and 7 and angle iron 13.

There is thus provided a space, as shown in Figs. 1, 2, 13a and 15a, defined at the ends by 10 walls 134 and 135, at the sides by the adjacent sides of the evaporator and condenser and at the bottom by the supporting flanges 50 and 81 which rest upon the center frame member 20, Fig. 9. Heat insulation 125, Fig. 2, of loose or molded 15 form is disposed in said space although for purposes of clarity this insulation is not shown in the perspective of Fig. 1. Heat insulation is placed between end walls 134, 135 and the headers of the evaporator, and is also secured on the 20 front side of the evaporator in space 126, Fig. 2.

A back plate 136, Fig. 1, covers substantially the entire rear side of the unit extending from the base channel 2, up to a point near or in contact with top piece 128, and is secured to the 25 rear standards 6, 10 and 8 as by any suitable means such as sheet metal screws or bolts. If desired strips of rubber or other suitable noise insulating material may be interposed between the standards and the sheet metal back 136. 30 As shown in Fig. 7 the upper edge of back plate 136 is bent slightly inwardly at 137 while a horizontal elongated opening 138 permits atmospheric communication in a manner and for a purpose to be described presently. The inside surface of 35 back plate 136 is provided with any suitable sound insulating material 139 which, in addition, serves as heat insulation between the relatively cool room air and the relatively hot condenser cooling air. This back plate or the insulation secured 40 thereto snugly fits against the edge of angle iron 16, Fig. 9, and also against the edge of flange 81 of the condenser.

From the foregoing it is seen that back plate 136, end walls 134 and 135, condenser plate 65 and 45 top cover 128, define a closed space or passage 140 leading from the top of the condenser fins out to the opening 138, thereby definitely confining the condenser cooling air in its path of flow from fan 92, through duct 78, ejector pan 69 and 50 over condenser 60 to opening 138.

End walls 134 and 135 and top cover 128, resting on evaporator flanges 31, definitely confine the flow of room air as it passes from fan 92 through the evaporator assembly to the outlet opening 55 130.

Due to the well defined passages for the flow of condenser and evaporator air, it is seen that the flow controlling walls of the motor-compressor compartment 141, Fig. 1, can be formed 60 partly by the cabinet to be described presently, while the remaining walls are formed by the top cover 128 and back plate 136. Thus there is the advantage of having a definitely formed motor-compressor compartment through which flow of 65 air may be positively guided and yet at the same time by merely removing the cabinet the equipment in the compartment is rendered conveniently accessible. If desired, under certain circumstances, the compartment for the motor-compressor or equivalent compression or refrigerating mechanism, may be closed at the front and end by insulated sheet metal secured to 70 standards 8 and 9.

Cabinet.—In order to facilitate not only the 75

manufacture and assembly of the unit as just pointed out above, but also to permit handling of the unit during transportation or installation without danger of marring or injuring the cabinet 5 in any way, and further to permit relatively easy inspection of or repair work to the unit while at the same time definitely forming a compartment for refrigerating mechanism, I have provided an improved cabinet so constructed and arranged 10 that it may be brought into full cooperation with the unit with minimum effort and without involving any special assembling with the mechanical features of the unit or the air ducts. To accomplish this the cabinet is provided with only three 15 sides and a top, and is arranged so that it has no metal contact with the unit frame or mechanism therein, and in addition has a pleasing appearance from any view within the room, this being possible by having the unit arranged so as to necessitate placing of the back against the wall 20 of the room.

As shown in Figs. 1, 2 and 6 the cabinet includes a front 150, ends 151 and 152, and a top 153, the rear corners terminating in vertical edges 25 154 and 155 while the rear top horizontal edge terminates at the edge 156 of the curved horizontal corner or molding. While various designs of cabinets may be used so as to please individual aesthetic tastes and allow harmonizing with the 30 interior decoration of offices or homes, yet in most of the designs it is preferred that as shown in Fig. 6 the lower edge 157 should be plain to permit it to fit within a suitably grooved portion 158, Fig. 20, formed around the top edge of a foot molding 35 159. If desired the groove may be sufficiently large to permit felt or other sound insulating material to be interposed between the edge of the cabinet and the walls of the groove. It will of course be understood that while the cabinet has 40 been described as being made preferably of sheet metal, yet the principles herein outlined are equally applicable to a wood cabinet but in any event it is preferable that the foot molding 159 may be secured to the frame. This is accomplished, as shown in Fig. 4 and others, by the 45 provision of a pan 162 having the molding 159 integral therewith. It will be observed that the top edge of the foot molding lies a substantial distance away from the edges of the base channels 1 and 2 and end angles 3 and 4 or from any part 50 of the frame that might tend to obstruct the locating of the cabinet within the bottom pan 162. The pan and frame are then preferably secured together as by bolts passing through the pan and 55 flanges of channels 1 and 2 or other suitable means. There is preferably placed in the bottom of pan 162 a sheet of suitable insulation 162' upon which the frame rests.

As shown in Fig. 7 the rear top corner 156 of 60 the cabinet is adapted to overlie the top inclined edge 137 of back plate 136, there being preferably a small longitudinal strip of insulating material 164 interposed between the adjacent edges. As 65 shown in Fig. 8 in horizontal section the rear vertical corners also slightly overlap the back plate 136 along its vertical edges while vertical insulating strips 165 are interposed between the adjacent edges.

70 With the cabinet in position over the unit an air opening 170 provided in the cabinet top will register, Fig. 1, with room air opening 130 of top plate 128 while a horizontal flange of grille 171 will rest upon the cabinet top and a vertical flange 75 of the grille will project through opening 171 and

have a relatively close sliding fit with the inside of flange 131 extending around opening 130.

A room air inlet opening 172, Fig. 6, is provided in one end of the cabinet to receive, Fig. 20, a grille 173 to be described later in detail. The 5 other end of the cabinet may be provided if desired with a room air exhaust opening 174 to receive, Fig. 1, a grille 175 although under certain circumstances as will be described hereinafter this grille and opening may be omitted. A small 10 opening 190 is preferably provided in the end of the cabinet at the lower rear corner thereof to permit an electrical plug to extend therethrough for insertion within an electrical socket.

To further facilitate the flexible assembly of 15 the cabinet and unit I have provided as shown in Fig. 6 a dummy button arrangement for starting and stopping the unit. While the electrical equipment, per se, does not constitute a part of my present invention, yet the starting buttons and 20 coordinated motor controls for the compressor and blowers do form a part thereof insofar as the general unit is concerned and partially to that end it will be noted that I have diagrammatically shown a switch element 176 mounted on a suitable bracket 177 secured to and projecting inwardly from the corner standard 10. A push button 178 projects outwardly for axial actuation by a dummy push button 179 carried by the end of the cabinet. This dummy button may be of any 25 usual construction such as is employed for devices of this type, so that it will suffice to state that the button is normally pressed outwardly by a spring 180 and guided in a suitable plate 181. It will be noted that the adjacent ends of buttons or stems 178, 179 are spaced apart thus insuring that the cabinet may be easily placed in 30 position without any obstruction between these buttons and yet their relation is such that the unit may be properly started and stopped. Four 35 buttons have been shown, two of the same being used for starting and stopping the fan motor and the other two for starting and stopping the compressor-motor.

Atmospheric ducts.—To properly cool the condenser while maintaining proper conditioning of the room air it is necessary that the condenser heat be conducted to the exterior of the room. To accomplish this with the utmost ease and simplicity of construction for an air cooled condenser, together with high efficiency of operation, the unit is placed preferably adjacent a window or other suitable opening whereby my improved arrangement of passages and connections therefor will allow, in a simple and effective manner 55 positive flow of exterior atmosphere into the unit, over the condenser and back to the exterior.

As diagrammatically shown in Fig. 2, the wall 200 of a room has a window ledge 201 and vertically movable window 202. The window is shown 60 in slightly raised position with a sealing insert 203 held in place between the window and sill and extending across the entire width of the window opening so that the window is in effect closed. The sealing insert is provided with an opening 65 of just sufficient size to permit, Fig. 5, inlet and outlet ducts 204 and 205 to pass therethrough for communication with the exterior atmosphere, these ducts being hereinafter referred to as atmospheric passages or equivalent terminology. 70 These passages may assume various shapes to conform to the particular style of window or other opening and may be constructed from metal or other suitable material although in the specific embodiment of the invention herein shown the 75

atmospheric ducts comprise a sheet metal casing generally indicated at 210. A partition 206 divides the casing into the two ducts 204 and 205, the duct 205 opening at its rear vertical side 207 while inlet duct 204 is closed at its vertical side 208 and is open at the lower horizontal portion as indicated at 209. By having opening 209 extend downwardly it is covered by the upper side of the casing thus preventing rain or the like from being drawn directly into the inlet duct, this difficulty not being present with the discharge duct 205 due to the appreciable quantity of air being discharged during operation although where heavy winds prevail it may be desirable to have the outlet open downwardly to prevent unnecessary back pressure against the discharged air. Also if discharge duct 205 is sloped or turned down, or otherwise suitably covered, it will prevent admission of rain when the unit is not in operation, and it may also be desired to have suitable screens, filters or the like over either or both atmospheric passage openings to prevent ingress of undesirable objects or living organisms such as flies and the like.

25 As shown in Fig. 2 the atmospheric casing 210 extends through the proper size opening 203' in sealing insert 203 and thence through opening 138, Fig. 1, of back plate 136. The atmospheric casing has a relatively snug fit with opening 138 and projects only a slight distance inside thereof although if desired the casing around its perimeter may carry a flange 211 fitting against back plate 136.

Path of condenser air.—As shown in Fig. 5, partition 206 preferably will abut against the intermediate standard 10 so as to positively direct inflow of air, from opening 209 and passage 204, (Figs. 1, 3 and 5) down over the lubricant cooling coil 119 and motor casing 114 of the motor-compressor unit and thence into inlet 213 of condenser fan 94 up through the condenser assembly and out, Fig. 6, through the atmospheric passage 205 which has communication as shown in Fig. 3 with either part of or the major length of opening 138 in back plate 136. Air is also admitted to the other end of the opposed inlet type of rotor 93 by virtue of the air flowing down over the compressor and passing around the outside of the fan casing and thence entering the other inlet 214 which is axially opposed to inlet 213. The air can pass around the fan casing due to the clearance between the casing and cabinet such as shown in Fig. 2 at spaces such as 215, 216 and 217. If desired the atmospheric inlet and outlet both 55 may be within that portion of the opening 138 extending between the standards 6 and 8, but in this case, as diagrammatically indicated in Fig. 25, the condenser is divided in the center by a transverse vertical partition 204' extending from one side of a fan 94' upwardly to internal top cover 128. A partition 206' in the atmospheric duct casing which projects through the window will coincide with the condenser partition thus causing exterior air to be drawn in by fan 94' and down over one-half of the condenser, thence through the fan and up over the other half of the condenser to be expelled to the outside.

70 The sealing insert is made preferably of wood or other non-metallic material that may be readily hand-shaped to fit different sizes of windows, thus permitting the manufacturer to supply a standard size insert which may be cut down to fit any particular window, the insert being originally 75 provided with its preferably fixed size opening for

receiving the atmospheric duct of preferably fixed size.

Modified condenser cooling air passages.—In the modifications of Figs. 5, 25-27 the motor-compressor, evaporator assembly and blower, and general structural features are the same as shown in the preferred form and are accordingly given the same reference characters. However, the condenser cooling air flows over the condenser in different manners so as to obtain various advantages including, for example, a relatively short atmospheric duct that does not extend for the full length of the unit.

10 In Fig. 25 the condenser is substantially equally divided by a vertical partition 218 which extends from the internal top cover 128' down to the inlet 218a of a single inlet condenser fan 218b. End walls 218c and 218d and suitable front and back walls form closed passages leading to the fan inlet and away from the fan discharge. An 15 oil cooling radiator 218e corresponding to coil 119 and connected by pipes 218f to the compressor, is placed preferably near the inlet side of the fan 218b. This fan is driven by motor 98 which also drives room air fan 91 for circulating room 20 air over the evaporator, the structure and operation thereof being identical to the preferred form. This modified condenser arrangement operates by having outside air flow inwardly through an opening 218g, thence downwardly and over the 25 lubricant cooler 218e, into fan 218b from which the air is propelled upwardly through a condensate ejector pan 218h (corresponding to but shorter than pan 69 of the preferred form) and over the remaining half of the condenser to be 30 discharged to the outside through an opening 218i. A suitable atmospheric duct casing projecting through a window is associated with openings 218g and 218i, these openings of course being formed in the back plate of the unit corresponding to 35 136 of the preferred form.

40 In Fig. 26 the condenser is divided by a longitudinal vertical partition 120 which turns outwardly at 120a, to form inlet and outlet atmospherical ducts 120b and 120c. Partition 120 in combination with front and back walls 120d and 120e and suitable end walls form closed passages 120f and 120g leading respectively to the inlet of a fan 120h (similar to 218b) and from the tangential outlet thereof. These passages in elevation are inclined upwardly to provide a space beneath the condenser for the evaporator fan and common driving motor. The operation of this arrangement is believed to be clear in that outside condenser cooling air will be drawn in through passage 120b which extends through a suitable opening in a back plate of the unit, this opening being about equal to the combined length of openings 218g and 218i of Fig. 25. The air thence flows downwardly over the forward half of the condenser to the fan inlet and is discharged from the tangential outlet of the fan upwardly past the condensate ejector pan 120i and thence up over the rear portion of the condenser to be discharged to the atmosphere. The ejector pan 120i 45 extends for the full length of the condenser but only covers one-half the width thereof.

50 In Fig. 27 the condenser is divided by a longitudinal horizontal partition 122 so that outside air flows inwardly through a passage 122a and 55 thence over the group of condenser tubes in the upper half of the condenser and thence flows downwardly through a closed passage 122b which, due to being the full length of the condenser, may be relatively narrow thus requiring very little ad- 60 65 70 75

ditional width of the room cooler unit. Passage 122b communicates with the inlet of a fan 122c which is similar to the fan 218b of Fig. 25, the air discharging from the tangential fan outlet upwardly through a passage 122d and past a condensate ejector pan 122e (identical to ejector pan 69) and over the lower group of condenser tubes to discharge the condenser heat to the outside air through a passage 122f. In elevation the passages 122b and 122d are inclined upwardly, similar to the corresponding passages in the other forms, to provide a space beneath the condenser for the evaporator fan and common driving motor. In the modifications of Figs. 26 and 27 the lubricant cooling coil is disposed preferably adjacent the single inlet of the fans 120h and 122c in the manner generally shown in Fig. 25.

Room air passages and filter.—Reverting again to the preferred form as shown in Fig. 4 and particularly in the enlarged view of Fig. 20 the grille 173 which fits within opening 172, Fig. 6, has an inwardly projecting flange 225 of rectangular form extending around the grille for telescopic engagement with a rectangular flange 226, the side edge being open as at 227 while the inner side 228 is entirely closed except for a circular opening 230 into which is received an annular flange 231 of room fan 91. The bottom of rectangular flange 226 has an upwardly offset portion 232 extending entirely across the width of flange 226. The flange is supported at its lower side by an angle iron 233 secured in the corner of the offset portion 232 as by sheet metal screws, soldering or other suitable means and this angle iron in turn as shown in Fig. 21 is secured to the corner standards 6 and 7 as by suitable bolts 234. The top portion of the flange 226 is similarly provided with a transverse angle iron 235 which is also secured to standards 6 and 7 as by bolts 236.

A filter generally indicated at 237 comprises a frame preferably in the form of a sheet metal pan having a perforated vertically disposed back or bottom portion 238 turned at its edges to provide sides 239, these sides thence being turned inwardly to provide, Fig. 21, a rim 240. As shown in Figs. 20 and 21 the lower outer corner of the frame is pivotally supported on the offset portion 232 as by a pair of hinges 241. The filter proper may be of any material suitable for filtering purposes such as metallic wool, preferably non-corrosive, although fibrous or cellulose filters may likewise be employed, any of which are herein diagrammatically indicated at 243. The filter material is removably held in position preferably by a series of vertical rods or bars 244 whose lower ends as shown more clearly in Fig. 23 are bent outwardly as at 245 to be received in suitable openings in the lower rim 240 while the upper ends of the rods are offset as shown at 246 to provide a hinge joint in suitable openings in the upper horizontal rim 240. Hence in this construction with the rods in their holding position as shown, if it is desired to remove the filter a person may merely press inwardly on the lower ends of rods 244 to free the bent ends 245 from their openings thereby permitting the holding rods 244 to be swung vertically about the axis of the offset upper ends 246 to permit the filter material to be easily and directly removed. The holding rods 244 are preferably slightly bowed inwardly along their length so as to provide a spring effect in holding the filter material firmly and also for holding the rods in position.

75 To facilitate periodic cleaning of the filter and

thus avoid too long continued use thereof with consequent reduced efficiency, it is preferable that the filter be adapted to be moved into a position having at least a horizontal component of direction along its face without necessarily completely removing the filter from the unit. To accomplish the foregoing I have in one aspect of the invention as illustrated herein, Fig. 20, shown the hinges 241 previously described. These hinges will permit the filter to be swung outwardly to the dotted line position 237' whereupon by merely striking or tapping the filter frame, dirt or other foreign matter will be dislodged to fall into a suitable receptacle placed beneath which a person may desire to use. The filter may be held in its normal position by a suitable spring held latch 246 for engagement with any suitable projection such as a rivet head or the like, and if desired, the spring latch may be provided with a finger engaging portion to facilitate release of the latch.

Path of room air.—From the foregoing description it is seen, particularly from Figs. 4, 20 and 2 that the path of flow of the room air is from the room through the room air grille 173, thence through filter 237 into inlet 231' to be discharged upwardly by the room fan motor 91, through the spiral fan casing 92' which communicates with the right rear side of the plenum chamber in lower duct 45 of the evaporator assembly, the air passing upwardly around the sides of the drip pan 41 and thence between condensate deflectors 39 to then pass upwardly through the evaporator to be cooled thereby and thence discharged into the room through grille 171.

In Fig. 4 and others it will be noted that the motor side of fan casing 92' is completely closed, with the exception of a circular hole to receive the shaft of fan motor 90 for attachment to the fan rotor 91, by a plate 90'. The motor side of fan rotor 91 may also be of a solid plate 91' located with as little clearance as is mechanically feasible adjacent to plate 90'. This construction of the fan casing and rotor tends effectually to prevent any condenser air, which may surround the motor side of the evaporator 24 to be discharged into the room.

It will further be seen that the location of the various elements comprising the condenser and evaporator air ducts and passages, in the manner previously described, lend themselves to the creation of what amounts to a "pocket" of comparatively motionless air surrounding the outside of fan casing 92', with the obvious exception of the fan intake 231'. Since the coefficient of heat transfer from metal to air decreases greatly with the velocity of the air surrounding the metal, the constructional creation of the aforementioned "pocket" of nearly motionless air obliterates the need for insulating the fan casing.

Ventilator.—Ventilation for the room may be effected if desired by adding to the room a controlled quantity of fresh, filtered, dehumidified and cooled air without interfering with the normal operation of the unit and without necessitating usual cumbersome methods of bypassing a portion of the room air. To accomplish this in one specific aspect of the invention as shown herein, there is provided as shown in Figs. 3 and 20-22 a relatively narrow and short slot 250 having a valve 251 preferably of the balanced butterfly type pivotally adjusted on a horizontal axis by a shaft 252 journalled in end brackets 75

283. One of these brackets may be provided with a set screw 254 for positively engaging the shaft and thus holding it in any adjusted position, or if desired shaft 252 may be extended to the side of the unit externally thereof for convenient manual adjustment. But in any event the valve 251 may be adjusted merely by removing the end grille 173 from its cabinet opening and thus permitting direct access to the valve for adjusting the quantity of air flow therethrough.

The fresh ventilating air is diverted, Fig. 20, from the flow of condenser cooling air in lower duct 84 before passing over condenser 60 and being heated thereby. As shown more fully in Fig. 20 the air enters what might be termed a filter space or chamber 260 where the fresh air mixes with the returned room air to be passed through filter 237 for circulation over the evaporator 24 by fan 91.

Coordinated fan and compressor operation.—

As shown diagrammatically in Fig. 24, I have provided improved electrical circuits for controlling the compressor and fans so that the fans must be started before operation of the compressor thus insuring minimum possibility of excessive refrigerant pressure being built up in the compressor system, as would otherwise occur in the event the compressor was started and run unknowingly for an appreciable period of time without operation of the fan and yet it is desirable to be able to operate the fan without necessarily operating the compressor in order to have positive air circulation in the room if desired. To accomplish the above, fan motor starting button 275 is pushed inwardly to simultaneously connect the three sets of contacts 276 whereupon current may flow from supply lines 277 to fan motor 90. Connected to any two of the fan motor lead wires 278 is a circuit including wire 279, a pilot or solenoid relay 280, a wire 281 in which are connected in series an air vane relay generally indicated at 282, a pressure switch 283, a thermostat 284 and a thermostat or humidostat 285 all diagrammatically indicated. It will be noted that these switches are in the form of a pilot circuit for the compressor motor or motor starter and that accordingly any of the same may be omitted or if desired there may be inserted any additional switches functioning in response to any predetermined conditions such as temperature, humidity, air flow, abnormal temperatures in the elements of the unit or abnormal pressures in the refrigerating cycle or other various conditions or abnormal temperatures or humidity conditions of the internal or external air. With the four switches as shown, however, it is assumed that the air vane relay 282 is disposed either in the flow of the condenser cooling air, or in the flow of room air before it leaves the unit, so that the switch closes only when fan motor 90 starts circulation of the condenser or room air, thereby permitting the compressor motor to operate only if the fan ducts are free of any obstructions to the flow. For instance, a person might accidentally or intentionally cover the outlet grille 171 for the room air, or the atmospheric ducts might also have been accidentally covered or by chance after long use the filters may possibly become clogged. Pressure switch 283 is assumed to be in the condenser side of the refrigerating cycle and to be closed when the pressure is low or below a predetermined point. Hence with the refrigerating cycle relatively inert this switch will be closed to permit starting of the refrigerating system.

Switch 284 is assumed to be controlled by a thermostat responsive to the temperature of the condenser cooling air so that if this temperature is below a predetermined value this switch will be closed whereas if the condenser air rises to a danger point the switch will automatically open. Switch 285 is assumed to be responsive to room temperature adapted to be closed when the temperature is above a predetermined value and to open when below that value thereby to permit automatic starting and stopping of the compressor in response to room temperature conditions. Switch 285 may also be assumed as a combined humidostat and thermostat designed to be open only when the conditions of humidity and temperature are agreeable to the person or persons utilizing this air conditioning unit. It is also preferable that the other switches 282, 283 and 284 automatically open and close their contacts in response to their respective controlling conditions.

With the various controlling conditions normally adapted to have switches 282—285 in their closed position as above described, it is seen that the compressor motor may now be manually started by pressing push button 286 to simultaneously close the three sets of contacts 287, whereupon current flows through leads 288, thence across pilot contacts 289 to the compressor motor 114.

To stop the fan and compressor motors simultaneously it is only necessary to press the other push button 215, thus simultaneously disconnecting the three sets of contacts 278 to break the circuit to both the fan and compressor motors. However, if it is desired to stop only the compressor motor and allow the fan motor to continue operating, push button 281 is pressed in to disconnect the three sets of contacts 287 thereby stopping only the compressor motor.

General operation.—From the immediately foregoing description of the fan and compressor motor controls, it will be assumed that the various elements of the unit are normally functioning, in which case lubricating oil is being circulated by a suitable pump, not shown, from within the motor casing 114 upwardly through its center outlet 121 and through the finned coil or other suitable radiator 119 to be returned at 120 to the motor-compressor unit. This coil 119 is cooled by atmospheric air entering, Figs. 2 and 5, through inlet 209, and thence flowing through duct 204 and, Fig. 3, downwardly over the motor-compressor unit and coil 119 to be admitted to fan inlet 213, Fig. 3, and also admitted to the other inlet of said fan by flowing through ducts 215, 216 and 217, Fig. 2, around fan casing 92 to said other inlet 214, the air thence flowing upwardly from the fan rotor through the lower duct 84 of the condenser assembly and upwardly through ejector openings 15, Figs. 2 and 15a, to entrain by an ejector action any condensate which has accumulated therein from the evaporator to be presently referred to. The air thence flows upwardly through the condenser 60 and out to the atmosphere through duct 205 to discharge condenser heat.

Room air is circulated over evaporator 24, Figs. 1, 2 and 20, as by having the room air enter grille 173, see particularly Fig. 20, and thence flow through filter 237 and into inlet 231 of fan 96, from which the air is discharged as shown in Figs. 4 and 13b into a side inlet opening 53 of a lower duct 45 and thence flows upwardly as shown in Figs. 2, 4 and 13a around a drip or col-

75

lector pan 41 and thence past baffles 39 and upwardly over evaporator 24 to be discharged through the room air grille 171. The room air is thus continuously recirculated over the evaporator while if it is desired to add fresh air to the room, then as shown in Fig. 20 and others, valve 251 may be opened to any adjusted position to allow fresh atmospheric air from the condenser passage duct 78 to be admitted to chamber 260 10 to commingle with the circulated room air after which it passes through filter 237 and over the evaporator to be cooled and dehumidified before passing into the room.

From Fig. 3 it is seen that condenser fan rotor 15 93 is twice the axial length of room fan rotor 91 but they are of the same diameter and also have the same speed due to being driven by the common motor 90. Hence the condenser fan circulates a greater volume of air than the room 20 air fan, this being desirable in order to cool the condenser adequately.

If for any reason it is desired to exhaust directly a certain amount of room air to the atmosphere in case the room air should be vitiated, 25 such air is admitted from the room through grilles opening 175 shown in Fig. 1, where the air flows into condenser fan 92 and upwardly into condenser duct 78, over the condenser and out to the atmosphere through duct 205. The grilles opening 175 has preferably a fixed flow area although if desired suitable adjustable vanes may be provided on the inside of the grille. It is desirable under many conditions to omit this direct 30 exhaust room air such as through the grilles exhaust opening 175 and to use in place thereof, normal leakage of air out of the room around windows, doors or other usual sources of leakage in buildings. This leakage is made sufficiently positive for purposes of ventilation due to the 35 pressure of the room air being possibly slightly above the pressure of the outside atmosphere, this increased pressure being accomplished by the admission, through the ventilator valve 251, of fresh air which is under pressure in the condenser ducts.

45 During normal operation, humidity in the air is condensed on the surface of evaporator 24 and as shown in Fig. 2 this condensate drips downwardly into collector or drip pan 41 or is deflected by baffles 39 into this drip pan. An outlet 55, Figs. 2 and 13a, conducts the collected condensate over to the accumulator or ejector pan 69, it being noted that pipe 55, as shown in Fig. 15a, extends through a side of ejector pan 69 at a point above the flange 73 thereof, thus permitting the condenser and evaporator to be bodily removed from the unit frame without being obstructed thereby. The pipe 55 is herein shown above the bottom level of ejector pan 69, thus insuring flow of condensate from the evaporator 60 side to the condenser side. The condensate in ejector pan 69 is carried to the exterior atmosphere by being entrained in the upward flow of condenser cooling air to be carried into contact with the surfaces of the condenser which due to 65 being hot will cause evaporation of this moisture, thus to be carried outwardly with the stream of atmospheric air. On the other hand, if by chance any of the condensate which collects in pan 41 is carried upwardly into contact with the cool 70 evaporator, the moisture will merely drip down again with other condensed moisture and gradually flow over to the ejector side. Any condensate dripping down through the ejectors will fall into contact with the centrifugal fans and

thus be thrown upwardly into the path of the condenser air. In the case of both the evaporator and condenser the fins or surfaces thereof will be kept at least partially moist by the condensate, thus materially increasing the coefficient 5 of heat transfer of the condenser and evaporator.

From the disclosure herein, it is seen that I have provided a self-contained portable room cooler unit having its elements so constructed and arranged that they may effectively cooperate 10 not only to function in a highly efficient manner but also to provide a relatively simple and compact piece of apparatus of pleasing appearance and which may be economically manufactured in 15 quantity production while insuring dependable and quiet operation at relatively low cost together with absence of any inconveniences, annoyances or mechanical complications when placed in a room or office for immediate use on a hot summer day when the demand for such equipment 20 is the greatest.

Various changes and rearrangements of the parts may of course be made by those skilled in the art without departing from the spirit of the invention as set forth in the appended claims. 25

I claim:

1. A self-contained room cooler unit adapted to be placed in a room adjacent a window or other suitable opening in the room wall comprising, in combination, a refrigerant evaporator, 30 means circulating room air over said evaporator to cool the room air, a refrigerant condenser, and means for circulating exterior air through the window and over the condenser and thence out through the window to conduct away the condenser heat, including inlet and outlet ducts projecting to the window directly rearwardly from the upper portion of the rear side of the unit and a passage extending downwardly from said inlet duct to near the bottom of the unit and thence upwardly for communication with said 35 outlet duct. 40

2. A self-contained room cooler unit adapted to be placed in a room adjacent a window or other suitable opening in the room wall comprising, in combination, a refrigerant evaporator, 45 means for circulating room air over said evaporator to cool the room air, a refrigerant condenser and compressor, and means for circulating exterior air through the window and over the compressor and condenser and thence out through the window to conduct away the condenser heat, including inlet and outlet ducts each projecting to the window rearwardly from the upper portion of the rear side of the unit and entirely between the ends thereof and a passage 50 extending downwardly from said inlet duct to near the bottom of the unit and thence upwardly for communication with said outlet duct. 55

3. A self-contained room cooler unit adapted to be placed in a room adjacent a window or other suitable opening in the room wall comprising, in combination, a refrigerant evaporator, means for circulating room air over said evaporator to cool the room air, a refrigerant condenser, and means for circulating exterior air through the window and over the condenser and thence out through the window to conduct away the condenser heat, including a single atmospheric duct casing, having inlet and outlet duct 60 portions, projecting to the window rearwardly from the room cooler unit, said duct casing having a horizontal length not greater than that of the unit and having a vertical depth less than 65 one-half the length of the duct. 70

4. A self-contained room cooler unit adapted to be placed in a room adjacent a window or other suitable opening in the room wall comprising, in combination, a refrigerant evaporator, means for circulating room air over said evaporator to cool the room air, a refrigerant condenser, and means for circulating exterior air through the window and over the condenser and thence out through the window to conduct away the condenser heat, including a vertically narrow horizontally elongated opening in the rear side of the unit near the top thereof and an inlet and outlet duct casing removably receivable in said opening and adapted to project directly to the window rearwardly from the room cooler unit. 10
5. A self-contained room cooler unit adapted to be placed in a room adjacent a window or other suitable opening in the room wall comprising, in combination, a refrigerant evaporator, a refrigerant condenser disposed laterally of said evaporator to permit an upward flow of room air thereover, means for effecting flow of exterior air through the window and over the condenser and thence out through the window to conduct away the condenser heat, a room air inlet in the side of said unit and a room air outlet in the top of said unit, and blower means for circulating room air through said inlet and upwardly over said evaporator and thence out through said room air outlet. 15
6. A self-contained room cooler unit comprising means forming a compartment at one end of the unit, a refrigerating mechanism disposed in said compartment, means forming condenser and evaporator compartments extending from said refrigerating compartment to the other end of the unit, a condenser and an evaporator disposed in their respective compartments and supported in spaced relation from the bottom of said unit to provide a bottom compartment, and blower means disposed within said bottom compartment for circulating room air over said evaporator and for circulating cooling air over said condenser. 20
7. A self-contained room cooler unit comprising means forming a compartment at one end of the unit, a vertical axis-motor-compressor refrigerating unit disposed in said compartment, the room cooler unit having its width determined substantially by the compressor and the height by the vertical axis of the motor-compressor, means forming condenser and evaporator compartments extending from said refrigerating compartment to the other end of the unit, a condenser and an evaporator disposed in their respective compartments and supported in spaced relation from the bottom of said unit to provide a bottom compartment, and blower means disposed within said bottom compartment for circulating room air over said evaporator and for circulating condensing cooling air over said condenser. 25
8. A self-contained room cooler unit comprising a frame, a motor-compressor supported at one end thereof, an evaporator and a condenser supported by said frame and extending horizontally from substantially adjacent said motor-compressor to the other end of said frame, and means for effecting circulating room air over said evaporator and for circulating condenser cooling air over said condenser, including a blower having communication with said evaporator at a point near one end of said unit and a blower having communication with said condenser near the opposite end of said unit. 30
9. A self-contained room cooler unit comprising a frame, a motor-compressor supported at one end thereof, an evaporator and a condenser supported by said frame and extending horizontally from substantially adjacent said motor-compressor to the other end of said frame, and means for circulating room air over said evaporator and for circulating condenser cooling air over said condenser, including a blower having communication with said evaporator at a point near one end of said unit and a blower having communication with said condenser near the opposite end of said unit, and a motor disposed between said blowers and adapted to commonly actuate the same. 35
10. A self-contained room cooler unit comprising a horizontally elongated frame, a motor-compressor supported at one end thereof, an evaporator and a condenser supported by said frame and extending horizontally from substantially adjacent said motor-compressor to the other end of said frame, and means for circulating room air over said evaporator and for circulating condenser cooling air over said condenser, including a blower having communication with said evaporator at a point near one end of said unit and a blower having communication with said condenser near the opposite end of said unit, and a motor disposed between said blowers and adapted to commonly actuate the same, said motor and blowers being disposed beneath said evaporator and condenser, and the axis of said motor and blowers extending in the elongated direction of the frame starting from near the motor-compressor. 40
11. A self-contained room cooler unit comprising a condenser, an air duct therefor disposed to direct flow of air in a substantially vertical direction, a refrigerating mechanism, a blower disposed at the lower portion of said condenser duct, and means for conducting outside air inwardly near the top of said unit and down over said refrigerating mechanism and thence into said blower and up through said condenser duct and over said condenser to be discharged outwardly through the upper portion of said unit. 45
12. A self-contained room cooler unit comprising a frame carrying a refrigerating mechanism, an evaporator, a condenser, air ducts for said evaporator and condenser arranged so that the air flows upwardly through each of said ducts and over the condenser and evaporator, and means for circulating air through said ducts. 50
13. A self-contained room cooler unit comprising a heat exchange element, means providing an air duct therefor, a frame for supporting said element and duct with the lower portion of said duct being suspended from said frame, and a blower disposed adjacent said suspended duct portion and communicating therewith for circulating air therethrough and over said heat exchange element. 55
14. A room cooler comprising a heat exchange element and an air duct therefor to provide substantially a unitary structure therewith, a frame for supporting said unitary structure in a substantially vertical position, the lower portion of said duct having a lateral opening, and a blower supported by said frame and disposed to the side of said unitary structure for communication with said lateral opening. 60
15. A room cooler comprising two complementary heat exchange elements and air ducts therefor, a frame for supporting at least one of said elements and its duct in spaced relation from 65
- 70
- 75

- the bottom of said frame, and blower means disposed beneath said spaced duct for communication with the other duct.
16. A room cooler comprising two complementary heat exchange elements and air ducts therefor, a frame for supporting at least one of said elements and its duct in spaced relation from the bottom of said frame, and blower means disposed beneath said spaced duct and having provision for communication with each of said ducts.
17. A room cooler comprising two heat exchange elements and air ducts therefor, a frame for supporting at least one of said elements and its duct in spaced relation from the bottom of said frame, and rotary blower means disposed beneath said spaced duct and having provision for communicating with each of said ducts in different angular directions with respect to the axis of said blower means.
18. A room cooler comprising two heat exchange elements and ducts therefor, disposed in substantially parallel vertical relation, and rotary blower means having different angularly directed outlets with respect to the axis of rotation, one of said ducts communicating with one outlet and the other duct with the other outlet.
19. A room cooler comprising two complementary heat exchange elements and ducts therefor, disposed in substantially parallel relation, a frame for supporting said elements and ducts, and rotary blower means disposed with its axis of rotation in substantial parallelism with that of said parallel elements, and said blower means having outlets directed upwardly for communication with said ducts.
20. A room cooler comprising two substantially parallel vertically disposed complementary heat exchange elements and ducts therefor, a frame for supporting said elements and ducts in spaced relation from the bottom of said frame, and rotary blower means disposed beneath at least a part of each of said ducts and having separate communication therewith.
21. A room cooler comprising two heat exchange elements and air ducts therefor, disposed adjacent each other, one of said ducts having an opening at one end and the other duct having an opening at the opposite end, and rotary blower means disposed adjacent said ducts and having angularly directed outlets adapted for communication with said openings of the respective ducts.
22. A room cooler comprising two heat exchange elements and air ducts therefor, disposed in substantially parallel vertical relation, a frame for supporting said elements and their ducts in spaced relation from the bottom of said frame, rotary blower means disposed with its axis in substantial parallelism with that of said elements and said axis being located substantially centrally of said elements, said blower means having tangential outlets which are directed in different angular directions with respect to said axis for communication with each of said ducts.
23. A room cooler comprising a frame having base members, standards carried thereby, an upper framework carried by said standards and adapted to provide two compartments, a condenser and duct therefor disposed in one of said compartments and supported by a part of said upper framework in at least a partially suspended position, an evaporator and duct therefor disposed in the other of said compartments and supported by another part of said upper framework in at least a partially suspended position, said duct being spaced from the level of said base members, and blower means supported by said base members beneath said ducts and communicating therewith.
24. A room cooler comprising a condenser and evaporator and air ducts therefor, disposed in substantially vertical parallel relation, one of said ducts having an opening at one end and the other of said ducts at the opposite end, a motor disposed beneath said ducts, separate blowers disposed at each end of said motor and commonly driven thereby, and means connecting one of said blowers to one of said openings and the other blower to the other of said openings in said ducts.
25. A room cooler comprising two heat exchange elements and air ducts therefor, disposed in substantially parallel relation, means for supporting one of said elements at a higher elevation than the other to provide an air chamber above the element having the lower elevation, and blower means for inducing flow of air through said ducts and over said elements.
26. A room cooler comprising horizontally elongated evaporator and condenser units disposed in substantially parallel relation but vertically offset from each other, air ducts therefor, means forming a passage over the top of the lower of said units, and blower means for inducing flow of air over said lower unit and through the passage formed thereover.
27. A self-contained room cooler unit comprising an evaporator, a condenser, a blower and passage for circulating room air over said evaporator, another blower and passage for circulating outside air over said condenser and back to the outside, a refrigerating mechanism connected to said condenser and evaporator to provide a compressor-condenser-expander circuit, and means for exhausting room air through said condenser passage to the outside air.
28. A room cooler comprising a frame, a condenser of substantially rectangular outline, an evaporator of substantially similar rectangular shape, said condenser and evaporator being provided with adjacent side plates disposed in substantially parallel relation, and means for supporting said evaporator and condenser by said frame with said side plates spaced apart to receive therebetween insulating material.
29. A room cooler comprising a heat exchange element, means providing an air duct, and means whereby said element and duct are adapted to be removably supported one by the other thereby normally forming a unit.
30. A room cooler comprising a heat exchange element, means forming a room air duct element, and one of said elements having slots to receive a portion of the other of said elements.
31. A room cooler comprising a heat exchange element having substantially vertical sides with an open top and bottom, means forming a duct leading thereto and disposed beneath the same, said duct in certain plan sections having the same outline as said element, an inlet in said duct whereby air may flow into said duct and upwardly over said element, and condensate control means disposed within said duct between said inlet and element and having a lateral condensate passage.
32. A room cooler comprising a heat exchange element, means forming a duct directly associated therewith for conducting air thereto, said duct having a lower portion with sides angularly disposed relative to each other and at least one

of which is inclined with respect to a horizontal plane, and an air inlet in said inclined side.

33. A room cooler comprising a heat exchange element, means forming a duct directly associated therewith for conducting air thereto, said duct having a lower portion of substantially rectangular form in certain plan sections and having at least one side which is inclined, and an air inlet formed in said inclined side near one end thereof.

10 34. A room cooler comprising a heat exchange element having an open top and bottom and closed sides, means forming a duct in substantial alignment with said element and adapted to provide a substantially unitary structure therewith, 15 means forming a shoulder along at least two sides of said unit, and means engaging said shoulder for supporting said unitary structure.

35. The combination set forth in claim 34 further characterized in that said duct is formed 20 of sheet metal and said supporting means comprising a flange formed from said sheet metal.

36. A room cooler comprising a heat exchange element having an open top and bottom whereby air may flow in a substantially vertical direction 25 over said elements, sheet metal sides for said element, end plate elements for said heat exchange element, flanges formed on certain of said elements and secured to the other of said elements, a frame for supporting said heat exchange element and end plates, and a duct leading upwardly to said heat exchange element also supported by said frame.

37. A room cooler comprising a heat exchange element having headers connected by refrigerant 35 passages, side plates on opposite sides of said element and projecting beyond said headers, means forming an air duct in substantial alignment with said element and within the space defined by said headers and plates, and end 40 plates secured to the projecting portions of said side plates to provide an insulating space between said headers and end plates.

38. A room cooler comprising a heat exchange element having headers and side plates, and 45 means forming an air duct element for said heat exchange element in substantial alignment therewith, one of said elements having provision to receive the other of said elements in nested relation therewith.

50 39. A room cooler comprising a condenser of substantially rectangular form in plan view, an air duct therefor in substantially vertical alignment therewith and of substantially the same rectangular formation as the condenser, said duct having a bottom surface inclined upwardly toward the condenser and provided with a substantially vertical inlet opening near the lower end thereof.

40. A room cooler comprising a cooling unit, 60 means for circulating room air over said unit for cooling the air and condensing moisture therein, a condensate ejector pan having openings therein whereby air may flow through said openings to effect an ejector action and thus entrain condensate with the flow of air, and means for circulating outside air through said ejector openings.

41. A room cooler comprising an evaporator and a condenser, said condenser having sheet 70 metal sides one of which projects higher than the other, means forming a duct leading upwardly to said condenser and being disposed in close juxtaposition thereto, means forming a passage leading over the said side which has the lower edge, means for circulating outside air

over said condenser and through said passage, and means for circulating room air over said evaporator.

42. A room cooler comprising a frame having base members secured together in substantially rectangular form, standards supported substantially at two corners of said frame at the same end thereof, intermediate standards supported by two of said base members at points intermediate their length, and an upper frame carried by 10 said standards for supporting heat exchange apparatus.

43. A room cooler comprising a frame having base members joined together in substantially rectangular form, a pair of end standards and a 15 pair of intermediate standards, projecting upwardly from and supported by said base members, an upper frame carried by all of said standards for supporting heat exchange apparatus, and a single end standard projecting upwardly 20 from substantially a corner of said base members remote from said other end standards, whereby said single standard and pair of intermediate standards generally define a space for receiving refrigerating equipment.

44. A room cooler comprising a frame having parallel structural channels whose flanges face outwardly, transversely disposed structural members connecting said channels, and standards projecting upwardly from said channels to support 25 heat exchange apparatus, certain of said standards being secured to said channels in outside overlapping relation to a corner thereof.

45. A room cooler comprising a frame having 30 a pair of substantially parallel structural channels, transversely disposed structural members connecting said channels to form a rectangular base, angle iron standards supported by and projecting upwardly from said base, said channels, transverse structural members and angle iron standards having interfitted relation with each other at a corner and welded together.

46. A self-contained room cooler comprising a frame having a refrigerating mechanism, an evaporator, a condenser, blower means for circulating air over said condenser and evaporator including a driving motor, a switch carried by 45 said frame for controlling said motor, a cabinet adapted to be independently removably disposed over said frame, and elements for supporting a dummy button by said cabinet in operative relation to said switch to effect actuation thereof, said dummy button and switch being so related that said cabinet may be removed without interference therebetween.

47. A room cooler comprising an evaporator, a condenser, motor-driven blower means for circulating air over said evaporator or condenser, a motor-driven compressor, a frame for supporting all of said elements as a self-contained unit, and means whereby said blower motor must first be operated before said compressor motor may be operated.

48. The combination set forth in claim 47 further characterized by the provision of means 60 whereby said blower and compressor motors are adapted to be individually manually started thereby permitting circulation of room air without operation of the refrigeration compressor.

49. A room cooler unit comprising a refrigerant 70 evaporator and air duct therefor, a refrigerant condenser and air duct therefor, means for circulating room air over said evaporator, means for circulating outside air over said condenser and then back to the outside for conducting condenser 75

- heat to the outside atmosphere, ventilating means for diverting air from the stream of condenser cooling air and admitting the diverted air to the room air at a point before the room air flows over said evaporator, thereby cooling the fresh air before entering the room, and a filter so disposed with respect to said ventilating means and the flow of room air that said fresh air and room air are first filtered before being cooled.
5. A self-contained room cooler comprising an evaporator and air duct leading thereto, a blower for circulating room air through said duct and over said evaporator, a cabinet enclosing said evaporator and blower and having an inlet, a filter disposed adjacent said inlet whereby room air is first passed through said filter before being cooled, and means for removing said filter through said inlet in the cabinet.
10. A self-contained room cooler comprising a frame, a motor-compressor unit supported thereby, an evaporator and a condenser supported by said frame, and fixed passage forming walls for at least a portion of the flow of air for said evaporator or condenser, and a cabinet removably disposed over said frame and adapted to definitely form the remaining walls of the passages for said flow of air.
15. A self-contained mechanical refrigerating room cooler comprising a frame, a motor-compressor unit supported thereby, an evaporator and a condenser supported by said frame, and fixed passage forming walls for at least a portion of the flow of air for said evaporator or condenser, said passage forming walls including an internal top cover extending over said condenser and motor-compressor unit and having an opening in alignment with said evaporator to permit flow of cooled room air therefrom.
20. The combination set forth in claim 52 further characterized in that said internal top cover has an upwardly extending flange surrounding the air passage over said evaporator, and a grille is supported by the top of the cabinet and has a portion telescoping with said flange.
25. A self-contained room cooler unit comprising a frame having a condenser, evaporator, blowers and air ducts therefor and refrigerating mechanism, a pan within which said unit is disposed, and a cabinet disposed over said unit and supported by said pan.
30. A room cooler comprising a frame, an evaporator and a condenser supported thereby in spaced relation from the bottom of the frame, a single inlet blower for said evaporator, a double axially opposed inlet blower for circulating air over said condenser to cool the same, and means forming walls around said blowers whereby condenser cooling air may flow around the blower therefor and thence into both inlet while the flow of room air is closed off from any substantial communication with said condenser cooling air.
35. A room cooler comprising a frame, an evaporator and condenser and air ducts therefor supported by said frame, a blower for circulating room air over said evaporator, a blower for circulating air over said condenser to conduct away condenser heat, a motor carrying the rotors of said blowers, the condenser rotor being of greater axial length than the evaporator blower, means for supporting said motor at points along the rotor axis one of which points is adjacent said motor and another of which is at a point intermediate the length of the condenser rotor, and a casing for said condenser rotor also supported by said frame independently of said motor support.
40. A self-contained room cooler comprising a refrigerant evaporator and air duct therefor, a refrigerant condenser and air duct therefor, means for supporting said condenser and evaporator and their respective ducts to permit air flow therethrough in substantially vertical directions, condensate collecting means disposed within said evaporator duct below the evaporator, condensate disposal means disposed within the condenser duct below the condenser, and means for conducting condensed liquid from said collector means to said disposal means.
45. A self-contained room cooler comprising a refrigerant evaporator and air duct therefor, a refrigerant condenser and air duct therefor, means for supporting said condenser and evaporator and their respective ducts to permit air flow therethrough in substantially vertical directions, condensate collecting means disposed within said evaporator duct below the evaporator, a condensate ejector pan disposed within the condenser duct below the condenser, and means for conducting condensed liquid from said collector means to said ejector pan to entrain the condensate by an ejector action of upwardly flowing air.
50. A self-contained room cooler comprising a frame, an evaporator and air duct therefor having condensate collecting means removably supported by said frame, and a condenser and air duct therefor having condensate disposal means also removably supported by said frame, said removable elements being removable independently of each other.
55. A self-contained room cooler unit adapted to be placed in a room adjacent a window comprising, in combination, a refrigerant evaporator, means for circulating room air vertically over said evaporator to cool the room air, a refrigerant condenser disposed to the rear of said unit and laterally of said evaporator to allow said vertical flow of room air over the evaporator, and means for circulating exterior air through the window and over the condenser and thence out through the window to conduct away condenser heat.
60. A self-contained room cooler unit adapted to be placed in a room adjacent a window comprising, in combination, a refrigerant evaporator, means for circulating room air over said evaporator to cool the air, a refrigerant condenser disposed at a lower elevation than said evaporator, means for circulating exterior air through the window and over the condenser and thence out through the window to conduct away the condenser heat, and means for disposing of condensate by conducting the same from the higher elevation of the evaporator to a lower point of elevation and then forcibly spraying the condensate into the flow of condenser cooling air.
65. A self-contained room cooler unit comprising, in combination, a refrigerant evaporator, means for circulating room air over said evaporator to cool the room air, a refrigerant condenser, means for circulating exterior air through the window and over the condenser and thence out through the window to conduct away the condenser heat, means whereby condensate from the evaporator is accumulated at a level below the condenser and evaporator, and means whereby said accumulated condensate is elevated into the outflowing condenser cooling air so as to be discharged therewith to the outside atmosphere, said circulating means for the condenser air includes a blower rotor and a duct leading from

the blower to the condenser whereby condensate may be thrown outwardly into the air stream upon contacting with said rotor.

63. A self-contained room cooler unit comprising separate compartments in which the compressor, condenser and evaporator are respectively disposed, a blower for circulating outside air downwardly through said compressor compartment and over the condenser therein, and thence upwardly through said condenser compartment and over the condenser therein, and means for circulating room air through said evaporator compartment.

64. A self-contained room cooler unit adapted to be placed in a room adjacent a window comprising, in combination, a refrigerant evaporator, means for circulating room air over said evaporator to cool the air, a refrigerant condenser disposed at a lower elevation than said evaporator, means for circulating exterior air through the window and over the condenser and thence out through the window to conduct away the condenser heat, and means including said exterior air circulating means for disposing of condensate by first conducting the same from the higher elevation of the evaporator to a lower point of elevation and then forcibly spraying the condensate into the flow of condenser cooling air.

65. A self-contained room cooler unit adapted to be placed in a room adjacent a window or other suitable opening comprising, in combination, a refrigerant evaporator, means for circulating room air over said evaporator to cool the room air, a refrigerant condenser, means including a blower rotor for circulating exterior air through the window and over the condenser and thence out through the window to conduct away the condenser heat, and means whereby condensate on the evaporator side may be thrown into the outside air stream upon contacting said condenser blower rotor and thereby be carried to the outside atmosphere in the flow of condenser cooling air.

66. The combination set forth in claim 1 further characterized in that said inlet and outlet ducts are disposed in superimposed relation to each other.

67. The combination set forth in claim 1 further characterized in that said inlet and outlet ducts are disposed in superimposed relation to each other, and said exterior air circulating means includes a single inlet blower communicating with said passage.

68. The combination set forth in claim 1 further characterized in that said passage has walls arranged so that the upwardly and downwardly extending portions of the passage are disposed one in front of the other.

69. The combination set forth in claim 1 further characterized in that one of the upwardly and downwardly extending portions of said passage includes means forming a substantially vertically extending duct spaced from the front of the unit, a blower included in the exterior air circulating means and having a scroll casing with a substantially tangential outlet communicating with the lower end of said vertical duct and the axis of the scroll being offset toward the front of the said vertical duct, and said passage also includes means for forming the other portion of said passage in front of said vertically extending duct for communication with an inlet of said blower casing.

70. The combination set forth in claim 1 further characterized in that said passage has walls arranged so that the upwardly and downwardly extending portions of the passage are disposed one in front of the other, said inlet and outlet window ducts being disposed in superimposed relation to each other for communication respectively with said upwardly and downwardly extending portions of said passage, and a blower located near the bottom of said unit and communicating with said upwardly and downwardly extending passage portions.

71. A self-contained room cooler unit comprising, in combination, a refrigerant evaporator, means for circulating room air over said evaporator to cool the room air, a refrigerant condenser, means for circulating exterior air through a window and over the condenser and thence out through the window to conduct away the condenser heat, means whereby condensate from the evaporator is accumulated at a level below the condenser and evaporator, and means whereby said accumulated condensate is elevated into the outflowing condenser cooling air so as to be discharged therewith to the outside atmosphere, said condensate discharge means having provision for directly discharging the condensate into the path of and in the direction of flow of the condenser cooling air at a point so that the condensate is carried into contact with the condenser and thereby tends to be evaporated by condenser heat.

72. An air conditioning unit comprising, in combination, a refrigerating system including a pair of heat exchange elements, blower means for circulating room air over one of said elements and outside air over the other of said elements, a filter through which said room air passes, and means for diverting a portion of said outside air and supplying it to the flow of room air before passing through said filter.

HENRY L. GALSON.

CERTIFICATE OF CORRECTION.

Patent No. 2,130,327.

September 13, 1938.

HENRY L. GALSON.

It is hereby certified that error appears in the printed specification of the above numbered patent requiring correction as follows: Page 15, first column, line 2, claim 62, strike out the word "outwardly"; line 9, claim 63, for "condenser" read compressor; and that the said Letters Patent should be read with this correction therein that the same may conform to the record of the case in the Patent Office.

Signed and sealed this 31st day of January, A. D. 1939.

Henry Van Arsdale

(Seal)

Acting Commissioner of Patents.
